UNITED STATES PATENT OFFICE.

WALTER A. MCFARLAND, OF WASHINGTON, DISTRICT OF COLUMBIA,
ASSIGNOR TO WOODRUFF MANUFACTURING COMPANY, OF WASH-
INGTON, DISTRICT OF COLUMBIA, A CORPORATION OF THE DIS-
TRICT OF COLUMBIA.

FILING-CASE.

SPECIFICATION forming part of Letters Patent No. 739,700, dated September 22, 1903.

Application filed July 8, 1903. Serial No. 164,725. (No model.)

To all whom it may concern:

Be it known that I, WALTER A. MCFARLAND, a citizen of the United States, residing at Washington, in the District of Columbia, have 5 invented certain new and useful Improvements in Filing-Cases, of which the following is a description, reference being had to the accompanying drawings and to the figures of reference marked thereon.

- 10 My invention relates to filing-cases, and is particularly designed to provide a construction by which a series of maps, tracings, blue-prints, drawings, or other papers or documents in sheet form may be stored or filed 15 in such manner that any one of the series may be gotten at without disturbing others. Maps, tracings, blue-prints of plans, and drawings are in many cases necessarily of such size as not to be readily filed or stored 20 unless rolled or folded and when needed for use must be unrolled or unfolded and cannot easily be made to lie flat. If filed or stored in flat condition, unless separate drawers are used for each sheet, it is a matter of difficulty 25 to withdraw any of a series of sheets other than the top one, and it is also a matter of difficulty to return to its proper position a sheet which has been withdrawn for inspection or use. By my present invention a construction is provided by which a series of 30 maps, tracings, or other sheets may be filed or stored in flat condition, one above another, without sacrifice of space, and any one of the series may be withdrawn or restored to its 35 proper place without disturbing the others of the series.

My invention consists in the construction hereinafter described and claimed by which the results above set forth are secured.

- 40 Referring to the drawings, Figure 1 is a vertical sectional view of a cabinet or series of drawers embodying one form of my invention, and Fig. 2 is a perspective view of one of the drawers of the cabinet shown in Fig. 45 1. Fig. 3 is a perspective view of the front end of a drawer, showing a modified form of my invention; and Fig. 4 is a side view of the construction shown in Fig. 3 with the drawer-front in raised position.

In the drawings, 1 is a cabinet provided 50 with the usual guides for supporting and guiding drawers 2. The drawers each comprise a bottom 3, sides 4, and back 5, all rigidly secured together in any convenient manner. 55

The front 12 of the drawer, instead of being rigidly secured to the sides and bottom, is carried by arms 6, which are pivotally connected to the sides 4 and normally rest in recesses 7, formed in the front ends of the sides. 60 The recesses 7 are preferably formed in the outer faces of the sides 4, so that the inner faces of the sides are unbroken. The recesses may have bottoms 7', as in Figs. 1 and 2, in which case the arms 6 when in normal 65 position rest on the bottom 7', and thus support the front of the drawer when the drawer is open, or may be open downward, as shown in Figs. 3 and 4, in which case the front of the drawer will fall downward, as shown in Fig. 3, as soon as the drawer is opened, and 70 will thus permit the contents of the drawer to be inspected.

The rear ends of the recesses 7 are included, as shown, to form shoulders 7², against which 75 the arms 6 rest when in raised position.

The arms 6 are preferably pivoted to the sides 4 by a pin 6', the outer end of which is supported by a plate 8, secured to the sides, 80 as shown.

The plates 9 are preferably set into the sides 4, so that their outer surfaces are flush with the outer faces of the sides. The arms 6 are preferably recessed to receive the plate 8. 85

The front ends of the sides 4 are preferably connected, as shown in Fig. 1, by a bar 9 of thicker material than the bottom, having a groove in its rear edge to receive a tongue formed on the front edge of the bottom.

The front 12 of the drawers are preferably 90 provided with drawer-pulls 10.

Within each of the drawers is arranged a series of superposed plates 11, which may be of strawboard, sheet metal, or other comparatively stiff material, preferably of a size to 95 fit the interior of the drawer.

In the use of my invention the maps, tracings, blue-prints, or other sheets to be filed

are placed each on one of the plates 11 and beneath the plate next above it, so that it will be kept in flat condition. When desired to get at any one of the maps, tracings, blue-
5 prints, or other sheets, the drawer containing the sheet desired is pulled out, and if the form shown in Figs. 3 and 4 is used the front of the drawer immediately drops, permitting the desired sheet to be selected. The front
10 ends of the plates 11 above the sheets desired are then raised and the front of the drawer is turned upward until the arms 6 rest against the shoulders 7² to form a support for the plates, which are allowed to rest in them.
15 The sheet desired may then be withdrawn and after inspection or use may be returned to place.

If the form of my invention shown in Figs. 1 and 2 is used, the front of the drawer will
20 remain in position after the drawer is opened and the sheet desired may be readily found, either from the top of the drawer or by raising the front of the drawer sufficiently to permit ready inspection. In this form of my in-
25 vention, as in the form shown in Figs. 3 and 4, as soon as the desired sheet is found the front ends of the overlying plates 11 are raised and the drawer-front is raised until its arms 6 rest against the shoulders 7² to form
30 a support for the plates and permit the desired sheet to be readily withdrawn or reinserted in position.

It will of course be understood that I do not desire to be limited to the precise construction
35 shown, and while the construction shown is that preferably used in the filing-cases constructed of wood it is obvious that the invention is equally applicable to filing-cases constructed of sheet metal.

40 Having thus described my invention, what I claim, and desire to secure by Letters Patent, is—

1. An open-ended drawer for filing-cases having its sides provided at their ends with
45 recesses, arms pivoted in said recesses and carrying the drawer-front at their free ends, and means for sustaining the arms and drawer-front in elevated position, substantially as described.

50 2. An open-ended drawer for filing-cases

having its sides provided at their front ends with recesses, arms pivoted in said recesses and carrying the drawer-front at their free ends, means for sustaining the arms and drawer-front in elevated position, and a series of plates arranged within the drawer and adapted to be supported at their front ends by the drawer-front when in elevated position. 55

3. In a filing-case having suitable guides for drawers, open-front drawers therein, arms pivoted to the sides of the drawers and carrying the drawer-fronts, means for sustaining the drawer-fronts in normal position, and means for sustaining the fronts in elevated position; substantially as described. 60

4. In a filing-case having suitable guides for drawers, open-front drawers therein, arms pivoted to the sides of the drawers and carrying the drawer-fronts, means for sustaining the drawer-fronts in normal position, 70 means for sustaining the drawer-fronts in elevated position and a series of plates arranged within the drawers and adapted to be supported at their front ends by the drawer-front; substantially as described. 65

5. An open-ended drawer for filing-cases, having its sides provided at their front ends with recesses, arms pivoted to the sides and normally resting against the bottoms of the recesses, a drawer-front carried by the free 80 ends of the arms, and a series of plates arranged within the drawer and adapted to be supported at their front ends by the drawer-front when the latter is in elevated position, substantially as described. 75

6. An open-ended drawer for filing-cases having its sides provided at their front ends with recesses having inclined rear walls, arms pivoted to the sides and normally resting against the bottoms of the recesses and adapted when in elevated position, to rest against the rear walls of the recesses, and a drawer-front carried by the free ends of the arms, 90 substantially as described.

In testimony whereof I affix my signature 95 in presence of two witnesses.

WALTER A. McFARLAND.
